UNITED STATES PATENT OFFICE.

ABRAM Q. ALLIS, OF NEW YORK, N. Y.

SPRING BED-BOTTOM.

SPECIFICATION forming part of Letters Patent No. 286,166, dated October 9, 1882.

Application filed December 28, 1882. (No model.)

To all whom it may concern:

Be it known that I, ABRAM Q. ALLIS, of the city, county, and State of New York, have invented a new and useful Improvement in 5 Spring Bed-Bottoms, of which the following is a specification.

This invention relates to that class of bed-bottoms wherein the lazy-tongs motion is employed; and the object of my invention is to 10 provide a simple means by which the bed-bottom may be locked to any desired width, so that it will remain rigidly in one position after it is locked to fit either a large or a small 15 size bedstead. Another object sought to be accomplished by my invention is to arrange the locking device so that it will act as a diagonal brace to prevent any and all end movement of the slats composing the bed-bottom, and which have attached to them the lazy-tongs motion. 20 The means by which I accomplish these results are fully illustrated in the accompanying drawings, in which—

Figure 1 represents a top view or plan with the top slats removed to show the mechanism; 25 Fig. 2, a side elevation; and Fig. 3, a plan, showing my improved bed-bottom having eight bottom slats instead of five, as represented in Fig. 1.

By reference to these drawings it will be 30 seen that one or more of the arms B, of which the lazy-tongs motion is composed, is extended until it reaches the slat to which the next lazy-tong arm is attached, as shown at h, Fig. 1. The slat thus reached is provided with a slot, 35 (shown at c, Fig. 1.) The end of the lazy-tongs arm thus extended is provided with a thumb-screw, (shown at k and m, Figs. 1 and 2.) The bolt portion of the thumb-screw is intended to work freely in the slot c; but it is so arranged that by tightening the thumb-screw the end of the arm B may be secured rigidly 40 to the slotted slat in any desired position, and the bed-bottom will remain in that position until the thumb-screw is loosened and readjusted. It will be thus seen that my improved 45 bed-bottom is superior to all others of its class, for the reasons that it can be adjusted to fit any size bedstead, and by means of the extended arm B and a slotted slat, c, it can be secured rigidly in that position until it is desired to readjust it to fit another size bedstead. 50

The extended arm B not only acts as a means to secure the bed-bottom to any desired width, but it also acts as a brace, which, being diagonally attached to the slats A, will prevent any 55 lateral or endwise movement of these slats, and it will be thus impossible for the bed-bottom to become askew or out of square.

Fig. 3 illustrates the same method of constructing an eight-slat bed-bottom, in which 60 the two inside slats and the two outside slats are preferably selected for attaching the device; but the locking device may be attached to any of the slats and the result will be the same; or, in order to more rigidly secure the 65 bed-bottom in position, the locking device may be attached to both ends of the lazy-tongs arm, as shown at h and h', Fig. 1. The same locking device can be made to operate also without the use of the slot or thumb-screw by 70 having a series of holes in the slat and a hole in the end of the arm B, passing a pin through it and one of the holes in the slat or by having the end of the arm B made in the form of a hook, so that it may be hooked to any of the 75 holes in the slat.

To construct my improved spring bed-bottom I generally use from five to eight slats like those shown at A to form the bottom, and the same number of slats to form the top side 80 of my bed. On the top side of the bottom slats I attach the jointed arms B, as described, and on the bottom side of the top slats I attach another set of jointed arms like those attached to the bottom slats. I then secure in 85 position the flat springs F, which are usually riveted to the jointed arms, both top and bottom. The coil-springs D are then inserted and secured in position, one end being fastened to the bottom slat and the other end fastened to 90 the top slat, as shown in Fig. 2, and my bed is complete.

I am aware that jointed arms forming a lazy-tongs motion, in combination with the top and bottom parallel slats, as well as coil-springs, 95 have been used heretofore, as shown in patent granted to me November 14, 1882, No. 267,316, and I do not claim such as my present invention; but

What I do claim, and desire to secure by 100 Letters Patent, is—

1. A spring bed-bottom provided with a

locking device consisting of a number of jointed arms, B, forming a lazy-tongs motion, pivoted to the slats A, and having the end of the said arms B extended and arranged to be adjustably attached to one or more of the slats A by means of slot c and thumb-screw or pins, as herein described, and for the purpose specified.

2. A spring bed-bottom formed of parallel slats top and bottom, as described, provided with the lazy-tongs-jointed arms B, having one end of one or more of said arms extended and arranged to be adjustably attached to the slat

or slats A by means of slot c and thumb-screw, as described, in combination with the spiral springs D and flat springs F, all as and for the purpose herein specified.

In testimony that I claim the foregoing improvement in spring bed-bottoms, as above described, I have hereunto set my hand this 14th day of December, 1882.

ABRAM Q. ALLIS.
